CLAIM

The ornamental design for a construction panel, as shown and described.

DESCRIPTION

FIG. 1 is a perspective of a construction panel according to the present invention.

FIG. 2 is a front top perspective view of a construction panel according to the present invention, included in the construction shown in FIG. 1.

FIG. 3 is a rear bottom perspective view of the construction panel of FIG. 2.

FIG. 4 is a front view of the construction panel of FIG. 2, the rear view being identical.

FIG. 5 is a top view of the construction panel of FIG. 2, the bottom view being identical.

FIG. 6 is a first side view of the construction panel of FIG. 2; and,

FIG. 7 is an opposite second side view of the construction panel of FIG. 2.

Any broken lines shown are directed to portions of the article which are not claimed, or to environmental structure which forms no part of the claimed design.

1 Claim, 4 Drawing Sheets
